[75] Inventor: **Winston Tak Yin Chu, Kowloon, Hong Kong****[73] Assignee:** **Marikon Resources, Inc., Arcadia, Calif.***Primary Examiner*—Dominic Simone
Attorney, Agent, or Firm—Pollock Vande Sande & Priddy**[**] Term:** **14 Years****[57] CLAIM****[21] Appl. No.:** **38,340**

The ornamental design for a signal transmitting unit for audio apparatus, as shown.

[22] Filed: **May 3, 1995****DESCRIPTION****[30] Foreign Application Priority Data**

Dec. 1, 1994 [GB] United Kingdom 2043673

[51] LOC (6) Cl. **14-03**

FIG. 1 is a front view;

[52] U.S. Cl. **D14/299; D14/299**

FIG. 2 is an underneath view;

[58] Field of Search D14/230-238,
D14/299; 343/700 R, 720, 721, 730, 731,
908; 455/344-346

FIG. 3 is a rear view;

FIG. 4 is a plan view;

FIG. 5 is view from one side;

FIG. 6 is view from other side; and,

FIG. 7 is a perspective view from front, above and one side.
